UNITED STATES PATENT OFFICE.

WILLIAM BUNTING MORTON, OF BEATRICE, NEBRASKA.

DISPLAY CASE.

Application filed August 1, 1921. Serial No. 488,975.

To all whom it may concern:

Be it known that I, WILLIAM B. MORTON, a citizen of the United States, residing at Beatrice, in the county of Gage and State 5 of Nebraska, have invented certain new and useful Improvements in Display Cases; and I do hereby declare the following to be a full, clear, and exact description of the invention, such as will enable others skilled in 10 the art to which it appertains to make and use the same.

The present invention relates to improvements in display cabinets for cakes, cookies and the like and has for an object to provide 15 certain changes and improvements over my prior Patent No. 1,328,185, granted January 18, 1920, for store cases.

The prior patent aforesaid was directed more particularly for use in the display and 20 sale of confectionery. An object of the present invention is to rearrange and make certain improvements to adapt a cabinet of this character for use in connection with the display and sale of cakes, cookies and other 25 merchandise of a like character. Merchandise of this sort is generally put up in tins or receptacles, and is sold directly therefrom, such tins having openings to display the goods and these tins are arranged on shelves 30 in a store where customers may view the contents and select the goods desired. This is found to be an unsatisfactory arrangement because when the contents of the tin are removed to such an extent that the display opening is arrived at, the goods lose 35 their regular appearance and the display becomes anything but attractive. Then, again, the sale of goods from tins of this kind is cumbersome as the tins must be re- 40 moved from the shelves and anything but a sanitary effect is presented to the customer.

It is therefore another object of the invention to provide an improved display case in which the different varieties of merchandise 45 will be displayed in separate compartments at the front portion of the case and in which tiltable bins are provided to receive the tins containing the goods in bulk at the back of the case, suitable marks or 50 other labels being made on the tins to agree with labels in the compartments so that a selection of goods may be made by the customer according to the label.

A further object of the invention resides 55 in providing certain improvements in the

construction of the case and in the display compartments, and in the arrangement and construction of the tiltable bins.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a perspective view with parts broken away of an improved display case constructed according to the present invention;

Fig. 2 is a fragmentary cross sectional view with one of the receptacles open;

Fig. 3 is a fragmentary rear view of the case;

Fig. 4 is a horizontal sectional view taken 75 on the line 4-4 in Fig. 2;

Fig. 5 is a plan view of a label employed.

Fig. 6 is a perspective view of one of the metallic strips.

Referring more particularly to the drawings, the case involves the use of a cabinet construction which is divided longitudinally by a number of uprights 1 and suitable parts secured thereto. At the front upper portion of the case are a number of shelves 2 arranged in stepped relation and having backs or risers 3 against which are placed mirrors 4 to reflect and give a doubled impression of the goods on display on the shelves 2.

End walls 5 are provided at the end portions of the cabinet and shelves and if desired division boards or walls 6 may be provided at suitable points in parallel relation with the end walls 5. These division walls 95 or boards 6 sub-divide the display portion of the case into a series of compartments one above the other and extending in horizontal rows, and as many of these compartments as are desired may be provided to accommodate a large or small store of cookies or other goods.

The merchandise is held upon the shelves 2 and prevented from falling down upon a sub-adjacent shelf by the use of transparent 105 walls 7. These walls are preferably glass strips being relatively low, and being transparent they do not interfere with the display of the goods. Both the mirrors 4 and the glass strips 7 are preferably held 110

in place by the use of metallic strips 8 having perforations 9 at suitable points to receive fastenings by which the strips 8 are secured to the end walls 5 and the division boards 6. Flanges 10 are turned over at the rear ends of the metallic strips 8 and take against the mirrors 4.

A pair of tongues 11 and 12 is turned at right angles to the plane of each strip 8 at the forward end thereof, and a central claw 13 is also bent from the material of the strip 8 inwardly of the tongues 11 and 12. The claw 13 is thus received as indicated in Fig. 4 upon the inner surface of the glass wall 7, while the tongues 11 and 12 engage the outer side thereof. These strips 8 are supplied at each end of each compartment and they therefore effectively hold both the mirrors 4 against the back walls 3 and the glass walls 7 in proper alignment and position against the front edges of the shelves 2.

A glass enclosing plate 14 fits over the various compartments and is supported for instance in a board 15 extending along the lowermost shelf 2 and at its upper end in the forward projecting edge portion of a shelf 16. Preferably felt or other suitable material 17 and 18 is provided along the edges of the glass plate 14. The glass plate 30 is also supported by the edges of the end walls 5 and division boards 6.

Beneath the display compartments is provided a relatively large space for the receipt of package goods. This space is closed 35 on its rear by a panel 19 lying against the uprights or structures 1. A base 20 is provided for the compartment and end walls 21 enclose the same. If desired, corner strips 22 may be placed in conjunction with the 40 end walls 21 in order to help support the shelving above and make for a stronger construction.

At the rear of the case, a number of partitions 23 is provided through which extend 45 rods 24 providing for the pivotal support of bins 25. These bins are separated by the partitions 23 and are of a shallow construction to receive the base portions of receptacles or tins 26 of the cakes, cookies or 50 other merchandise on sale. The bins 25 are provided with cut-out slots 27 in their forward lower portions to receive the rods 24 and to have detachable engagement therewith to permit of the lifting out of the bins 55 when required.

The rear portions of the bins rest upon beams 28 extending between the partitions 23. Stops 29 are provided upon the partitions 23 in position to catch the upper edges 60 of the bins when swung forwardly as indicated in the lower portion of Fig. 2. These stops 29 are preferably small strips of wood or other material having means to secure them to the partitions 23 and lying in contact with an extensive edge surface of the 65

bins when raised. The bins are all preferably numbered as indicated at 30 in Fig. 3 in order to correspond with numbers shown on display backs or labels 31 illustrated more particularly in Fig. 5 and placed in 70 each of the display compartments.

These labels identify the goods in the display compartments by numbers and the bins containing like numbers enables the customer to order by number from the display and the clerk to fill the order from the bins behind the counter without interfering with the display or subjecting the customer to the impropriety of witnessing the removal of the goods from the tins 26 and their packaging. The tags or labels 31 also contain names of the goods and may also contain the price thereof.

In use, a customer at the front portion of the case may view through the glass 6 85 the various different articles on display and having made a selection communicates the number thereof to the clerk behind the counter who serves the customer from the tin of the corresponding bin. The arrangement 90 of the bins enables a clerk to swing the receptacle 26 forwardly to a position where the relative location of the pivot rod 24 and the stop 29 permits of gravity holding the parts in this forwardly tilting position 95 until pushed backwardly.

The lid of the tin is swung upwardly as indicated in Fig. 2 to expose the contents and it will be noted that the bins are arranged in a terraced disposition so that the 100 lid may be raised against the upper bin and may be swung sufficiently far to enable the lid to remain open without putting this burden continually upon the clerk. The arrangement is such that the contents of 105 the receptacle 26 may be exposed for a desired interval without any attention of the clerk, which leaves the clerk free to remove the contents with one hand while he holds a sack or bag in the other to receive same.

The mirrors 4 of course create an impression of a large display of the articles and the glass walls 7 prevent the articles from escaping out of place or on to lower shelves while at the same time not obscuring the 115 articles in the forward portion. If the glass 6 is removed, the wall 7 may be moved upwardly for the purpose of cleaning, polishing or replacement.

Package goods are adapted to be placed 120 on the bottom 20 in the enlarged display space beneath the compartments, and in the tray 16 at the top of the cabinet, such package goods being suitably labeled and priced from which customers may help themselves 125 and subsequently pay for same at a cashier's booth, for instance near the exit.

It will thus be appreciated that the improved cabinet constitutes both a self service vending case, and a display and separate 130

bin structure from which merchandise is sold while the displays remain constantly in the same attractive position and are not touched or tampered with in any wise on the 5 making of a sale.

It is obvious that various changes and modifications may be made in the details of construction and design of the above specifically described embodiment of this invention 10 without departing from the spirit thereof, such changes and modifications being restricted only by the scope of the following claim.

What is claimed is:—

A display case comprising separate bins 15 for containing different varieties of goods, a front portion having shelves divided into compartments for containing the various goods on display, strips lying in said compartments at the sides thereof, each strip 20 having claws at the front edge thereof with a tongue spaced from said claws, and transparent strips engaged between the claws and tongues and located at the front portion of the compartments.

WILLIAM BUNTING MORTON.
